UNITED STATES PATENT OFFICE

104,643

DESIGN FOR A THERAPEUTIC APPARATUS CABINET

Walter Dorwin Teague, New York, N. Y., assignor to The Crosley Radio Corporation, Cincinnati, Ohio, a corporation of Ohio

Application March 1, 1937, Serial No. 67,921

Term of patent 14 years

To all whom it may concern:

Be it known that I, Walter Dorwin Teague, a citizen of the United States, residing in New York, in the county of Queens and State of New York, have invented a new, original, and ornamental Design for a Therapeutic Apparatus Cabinet, of which the following is a specification, reference being had to the accompanying drawing, forming part thereof.

In the drawing:

The figure is a perspective view of a therapeutic

apparatus cabinet showing my new design. The reverse side of the cabinet is similar in shape and decoration to the side shown in the perspective view in the drawing excepting that the handle for the sliding door appears only on the side of the cabinet shown.

I claim:

The ornamental design for a therapeutic apparatus cabinet, as shown and described.

WALTER DORWIN TEAGUE.
